UNITED STATES PATENT OFFICE.

CORNELIUS DWYER, OF AMSTERDAM, NEW YORK.

METHOD OF INSTALLING WATER-CLOSET BOWLS.

Application filed September 22, 1920. Serial No. 411,996.

To all whom it may concern:

Be it known that I, CORNELIUS DWYER, a citizen of the United States of America, residing at Amsterdam, in the county of

5 Montgomery and State of New York, have invented certain new and useful Improvements in Methods of Installing Water-Closet-Bowls, of which the following is a specification.

10 A primary object of the present invention is to provide for easily and quickly installing bowls upon the soil pipe of a building regardless of the varying depth of the bottom recesses in the bowls and sinks now manufactured, the bowl or sink being perfectly fitted to the soil pipe and seated upon the finished floor in the manner illustrated.

15 A still further object of the invention is the provision of means for seating bowls and the like upon finished floors in connection with soil pipes insuring a tight joint and avoiding the possibility of breaking the bowl or sink, the plumber being enabled to position a coupling upon the soil pipe beneath the bowl or sink properly positioned for evenly resting the lower edges of the base upon the finished floor.

20 With these general objects in view the invention consists of the method hereinafter described and the embodiment of parts for carrying out the same as illustrated in the accompanying drawings, and in which like reference characters designate corresponding parts throughout the several views.

25 In the drawings,

Figure 1 is a view of the attaching end of a soil pipe and the adjacent portion of the floor in vertical section with the soldered nipple in position and with a portion of the base of a bowl shown in vertical section installed upon the soil pipe,

30 Figure 2 is a top plan view of the flange connection employed between the soil pipe and bowl,

35 Figure 3 is a bottom plan view of a portion thereof showing one of the bowl-receiving slots,

40 Figure 4 is a fragmentary sectional view taken upon line VII—VII of Fig. 2, with the nipple removed from the flange,

45 Figure 5 is a horizontal sectional view through a bowl installed after the manner of my invention with one of the bowls shown in section and one removed,

50 55 Referring more in detail to the drawings, I have shown for purposes of illustration

the soil pipe 11 projecting upwardly through a floor 12 for the purpose of installing a closet bowl 13 thereon.

55 The annular recess 14 surrounding the outlet extension 15 of the bowl 13 varies in depth in different bowls with respect to the bottom face 16 of the bowl thereby usually rendering it difficult to connect the extension 15 within the soil pipe 11 and accurately seating the bottom 16 of the bowl flatly upon the finished floor 12.

60 My invention provides a flange connection 17 best illustrated in Figure 2 of the drawings comprising a ring or annular flange 18 screw-threaded upon a central nipple 19.

65 The nipple 19 has a beveled or tapered outer face for reception within the open end of the soil pipe 11 which may be slightly flared for this purpose as at 20, nipple 19 being secured to the portion 20 by solder 21.

70 The nipple 19 is easily positioned with its upper edge above the floor 12 a distance equal to the depth of the recess 14 and the nipple is then secured by solder 21 to the pipe end 20 in this position.

75 The flange 18 is then mounted upon the nipple 19 by means of the screw threads 29 and the bowl 13 is positioned right side up with the outlet extension 15 inserted within the nipple 19 and with the roof 22 of the recess 14 seated upon the top of the flange 18 as best illustrated in Figure 1 of the drawings, and at which time the bottom 16 of the bowl 13 is accurately positioned upon the finished floor 12. The usual attaching bolts 30 are in position through the radial slots 31 of the bowl 13 when installed in this manner, and the squared heads 32 of the bolts 31 are projected downwardly through the squared end portions 33 of slightly arcuate slots 34 provided in the flange 18, it being understood that the usual washers 34 and retaining nuts 35 are provided upon the 80 upper end portions of the bolts 30.

85 Figure 2 is a top plan view of the flange connection employed between the soil pipe and bowl,

90 Figure 3 is a bottom plan view of a portion thereof showing one of the bowl-receiving slots,

95 Figure 4 is a fragmentary sectional view taken upon line VII—VII of Fig. 2, with the nipple removed from the flange,

100 Figure 5 is a horizontal sectional view through a bowl installed after the manner of my invention with one of the bowls shown in section and one removed,

105 Referring more in detail to the drawings, I have shown for purposes of illustration

110 the soil pipe 11 projecting upwardly through a floor 12 for the purpose of installing a closet bowl 13 thereon.

U-shaped ledges 36 inwardly of the slots 33 flush with the upper face of the flange 18 are adapted to receive the bolts 30 with the heads 32 beneath the ledges 36 upon slightly turning of bowl 13 axially of the extension 15 to place the bowl in its proper direction upon the floor 12 and at which time, the nuts 35 may be tightened upon the washers 34, thereby locking the bowl 13 to the flange 18 and drawing the bottom face 16 of the bowl tightly against the floor 12.

A water and gas tight joint is easily formed in this manner between a bowl or sink and the soil pipe 11, it being seen however, that the joint may also be easily disconnected by substantially reversing the operation herein described. The connection nipple 19 is readily soldered to any soil pipe at the required elevation for accurately installing any bowl or sink regardless of the 10 depth of the recess 14 provided in the base thereof. The flange connection 17 is serviceable with any form of soil pipe and bowl or sink.

Having thus described my invention, what 15 I claim as new and desire to secure by Letters Patent, is:—

Means for attaching bowls to soil pipes wherein the upper end of the soil pipe is

outwardly flared and projects thru and above an opening in the flooring, an externally tapered nipple permanently secured to the flared end of said soil pipe and extending above the same, a ring threaded to said nipple, and a bowl adapted to be secured to said ring and rest upon the upper edge of said nipple, said bowl having an annular recess of substantially equal depth surrounding an outlet extension of greater axial length than the depth of said recess, said extension positioned within said nipple, and said ring being of less axial length than the depth of the said recess and wholly positioned therein.

In testimony whereof I affix my signature.

CORNELIUS DWYER.
